UNITED STATES PATENT OFFICE.

GUSTAV THOMAS, OF LOS ANGELES, CALIFORNIA.

GRADING-MACHINE.

1,033,291.

Specification of Letters Patent.

Patented July 23, 1912.

Application filed November 6, 1911. Serial No. 658,677.

To all whom it may concern:

Be it known that I, GUSTAV THOMAS, a citizen of the United States, residing at Los Angeles, in the county of Los Angeles and State of California, have invented new and useful Improvements in Grading-Machines, of which the following is a specification.

This invention relates to improvements in grading and sorting machines and particularly such as are adapted for the grading of vegetables, fruits, or any other articles.

It is an object of the invention to provide a device which will be capable of handling vegetables or fruits which run in different sizes so as to separate the various sizes from each other.

It is a particular object of the invention to provide a mechanism which will separate the materials without danger of injuring or crushing them.

Figure 1 is a side elevation of the improved grading or sorting machine. Fig. 2 is an end elevation of the same, the feed trough for delivering materials to the machine being shown in section. Fig. 3 is an enlarged detail sectional view through one of the sets of gearing employed for adjusting the grading belts with respect to each other. Fig. 4 is a side elevation of the grading machine looking at the opposite side of the same from that shown in Fig. 1. Fig. 5 is a detail transverse sectional view taken upon the line 5—5 of Fig. 4. Fig. 6 is a fragmentary detail sectional view taken upon the line 6—6 of Fig. 5. Fig. 7 is an enlarged detail sectional view of one end of one of the belt carrying rolls, the gearing for turning the same being shown in elevation. Fig. 8 is a detail sectional view taken through the bearings employed for holding the gearing shown in Fig. 7 in place. Fig. 9 is a detail view showing the end of one of the lower rollers upon an enlarged scale. Fig. 10 is a detail plan view of one of the plates employed at the upper end of the belts for holding the auxiliary belts which are employed in connection therewith in position.

The details and features of the invention will now be more particularly described, reference being had to the said drawing in which 10 indicates a main frame made up of side portions and transverse connecting bars, the said side portions of the frame having 55 their longitudinally extending beams or bars arranged so as to incline downwardly from

the front end of the machine toward the delivery end thereof. The said frame is thus formed with an elongated front end frame 11 and a shorter end frame 12 at the discharge end of the device. The delivery end of the machine is also provided with a second frame 13 preferably off set and shaped to properly support receiving buckets or bins into which the separated materials may be delivered.

Upon the upper front end of the machine a discharge spout housing 14 is provided which receives the end of a supply trough 15 in which any suitable conveyer 16 is operated for carrying the materials to be graded, to the machine. The belt 16 passes over a roller which is connected with a pulley 17 mounted outside the trough and connected by means of a cross belt 18 with a similar pulley 19. The pulley 19 is connected with a paddle wheel 20 which is mounted within the spout housing 14. The paddle wheel is thus turned in an opposite direction to the roller over which the belt 16 passes and the paddles which are preferably of flexible material will operate to force the materials downwardly to the discharge outlet of the said spout housing 14. The housing is arranged to deliver the fruit, vegetables or other materials between sorting aprons or belts which will be hereinafter described.

The fruit, vegetables or other materials to be graded are acted upon by opposing aprons 21 which are usually set with their upper portions somewhat wider apart than their lower portions, as will be understood by reference to Figs. 2 and 5 of the drawing. The said aprons are inclined also from the front end of the machine toward the rear end thereof, the aprons extending approximately parallel with the inclined framing of the machine. The aprons may be made of canvas or other suitable flexible material and extend approximately the full distance from the front frame 11 to the rear frame 12. The said aprons run upon upper rollers 22 and lower rollers 23 which are carried by shafts 24 and 25. The ends of said shafts are journaled in bearings which are carried by adjustable bars 26. The said bars 26 are arranged adjacent to the rollers 22 and 23 and are adapted to be adjusted with respect to each other for controlling the angle at which the aprons stand with respect to each other.

The bars 26 at the front ends of the ma-

chine are connected with the bars 26 at the rear end of the machine by longitudinally extending bars 27 and 28, thus forming frames which carry the said bearings of the 5 rollers 22 and 23. The upper and lower ends of each of the bars 26 are bifurcated at 29 and are adapted to slide upon guide rails 30 secured to the cross bars of the end frame 11. It will thus be observed that by moving the 10 said bars 26 with respect to each other, the position of the frames can be altered or adjusted. The said frames are positively held in adjusted position with respect to the sides of the frame 10, by means of screw rods 31 15 and 32 arranged at the upper and lower ends of the bars 26.

The screw rods 31 extend past the ends of the bars 28 and are secured to the ends of the bars 27, the said latter bars being made 20 longer than the bars 28, for this purpose. The screw rods 32 are secured to the bars 28 as clearly shown in Fig. 3. Each of the 25 said screw rods engages a screw threaded sleeve 33 which is mounted in bearings 34 formed in the side framing of the machine. Splined to the said sleeve are gears 35 and 36 which are arranged to mesh with each other. The sleeves 33 of the rods 32 are also provided with sprocket wheels 37 and a 30 sprocket chain 38 connects the sprocket wheels 37, at the front and rear ends of the machine both at the top and bottom of the aprons as shown in Fig. 1 of the drawing.

A handle or other turning means may be 35 applied to the projecting end of the sleeve upon the rods 31, for turning them as indicated in dotted lines in Fig. 3. In this manner the sleeves upon all of the screw rods at the top of the aprons may be operated simultaneously and so also, all of the screw rods at the bottom of the aprons may be operated simultaneously. The rods 31 and 32 40 of each group of gears are threaded alike, so that the sleeves which are turned by the 45 intermeshing gears 35 and 36 will operate to move the said screw rods in opposite directions with respect to each other, and thus either draw the apron carrying frames toward each other or separate them. The 50 frames are usually adjusted in this manner so that the upper ends of the aprons are wider apart than the lower ends, and as the fruit or materials to be graded, work their way downwardly along the inclined belts 55 the smaller fruit will reach the lower positions between the belts, while the larger fruit will be discharged from higher positions therebetween.

The bearings 39 for the upper rollers and 60 their shafts 24 are secured to the bars 26 a short distance below the bars 27 and 28, while the bearings 40 for the shafts of the lower rollers are secured to said bars 26 near the lower longitudinal bars 27 and 28. The 65 aprons are operated by the turning of the

rollers 22 and the rotation of said rollers is accomplished by means of bevel gears 41, which are rigidly secured to the ends of the shafts 24. The said gears 41 mesh with corresponding bevel gears 42 which are splined upon transverse shafts 43, having bearings upon the upper frame 11 of the machine. The hubs of the gears 42 are elongated opposite the ends of the shafts 24 and are formed with peripheral grooves in which are placed securing straps 44, which straps permit of the turning of the hubs, but hold the gears in their positions upon the shafts 43.

The straps 44 are secured to blocks 45 which have bearings 46 upon their inner faces adapted to receive journaled ends 47, formed upon the ends of the shafts 25 as clearly shown in Fig. 8. The structure is such that the rollers may be adjusted toward or away from each other, and yet the gearing upon the shaft 42 which turns said rollers, can slip back and forth upon the said shaft and will always be in position to actuate and rotate the said rollers 22. One 90 end of the shaft 43 carries a sprocket wheel 48, which is connected by means of a sprocket chain 49 with a sprocket wheel 50 carried by a shaft 51, also journaled upon the front end of the machine. A pulley 52 carried by the shaft 51 may be connected with any suitable source of movement, for rotating the said shaft and driving the sprocket mechanism. An adjustable sprocket wheel 53 also engages the said sprocket 95 chain 49 for controlling its tension. An adjustable bar or standard 54 carries the said wheel 53 as shown in Fig. 4.

Since the aprons 21 are mounted upon inclined rollers there is a tendency for the 100 said aprons to work downwardly on said rollers toward the lower end of the machine. To prevent such action, the upper ends of the aprons are so connected to the upper ends of the rollers, over which they pass, that they cannot slip longitudinally of the said rollers. In order to accomplish such a holding of the aprons, auxiliary belts 55 are employed and mounted upon the upper ends of the inclined rollers 22 and 23. The said auxiliary belts 55 are preferably narrow belts, usually of leather, and are arranged to engage offset portions upon the ends of the said rollers 22 and 23, formed by reducing the diameter of the said rolls for a short distance. In order to accommodate the different belts upon the rollers and to compensate for their slipping to a slight degree with respect to each other, as they necessarily do in passing around the same rollers, sleeves 56 110 are provided upon the reduced ends of the rollers as clearly shown in Fig. 7. The said sleeves are also formed with inwardly projecting detents usually smooth ended screws 57, which engage annular grooves 58 formed 115

near the ends of the rollers. The aprons 21 are secured to the auxiliary belts 55 by means of hook shaped clips 59, which are secured to the edges of the aprons 21 and 5 slip upon the outer edges of said auxiliary belts 55.

The belts 55 are rested against plates 60 which are arranged near the upper ends of the rollers 22. Each of the said plates 60 is 10 formed with an aperture 61 adapted to fit upon the reduced end of the rollers 22. The portion of the plate which surrounds the said opening 61 is also formed with an edge flange 62 which guides the movement of the 15 said belt 55 which engages it. Each of the said plates 60 is held in proper position with respect to the frames which carry the aprons, by means of rods 63, which are bolted to said plates and extend outwardly 20 therefrom between the laps of the aprons. The said bolts are also clamped as at 64 to longitudinal bars 65 which connect the bars 26 of the frames at intermediate points.

The structure above described not only 25 permits the proper holding of the aprons against slipping upon the inclined rollers, but is of such a character that any slight tendency of the belt 55 to slip upon the rollers in accommodating itself to its different 30 positions will be permitted by the engagement of the belts with the sleeves 56.

In operating the aprons they are moved 35 so that their inner opposing surfaces are carried upwardly, thus continually tending to lift the fruit or material assorted and the smaller articles will find their way toward the bottom. The lower frame 12 of the machine is provided with a series of 40 spouts 66, 67, 68 and 69 which are adapted to deliver the assorted material at different points between the aprons. The lower spout 69 delivers material into a box or receptacle 70, preferably resting upon the lower frame of the machine. The spout 67 45 delivers material into a box or receptacle 71 mounted upon the supports formed on the frames 12 and 13. The other spouts 66 and 68 deliver their material upon endless belts or conveyers 72 and 73 respectively 50 which are adapted to carry the said materials to boxes or receptacles 75 and 74 mounted outside the frame 13, as clearly shown in Figs. 1 and 4 of the drawing. Adjustable spouts 76 and 77 may be provided 55 for each of the said conveyers so as to insure the proper delivery of the materials therefrom to the said boxes 74 and 75. The said conveyers 72 and 73 may be driven in any desired manner, but are usually driven 60 by means of sprocket wheels 78 and 79 carried by the shafts of their inner rollers, and the sprocket wheels engage a sprocket chain 80 which passes about them, and about an intermediate sprocket wheel 81, and thence 65 around a sprocket wheel 82 carried by the

roller of the conveyer belt 16. The said sprocket chain is driven by means of sprocket wheel 83 secured to the shaft 43, which is connected with the actuating mechanism of the machine. In this manner 70 a single sprocket chain may be made to operate the feed conveyer and the delivery conveyers of the device.

In using the device the vegetables, fruits or other articles are delivered to the machine upon the conveyer 16, falling into the box 15 where they are prevented from clogging by means of the paddle wheel 20. The materials fall between the aprons 21 and as they work their way down the incline of 75 said aprons, the smaller articles will fall to the bottom, others taking their place at intermediate points according to their size and being delivered through the spouts at the end of the machine into the respective 80 boxes designed for their reception. The 85 culls and smallest articles will fall into a box or receptacle 84 placed beneath the open space between the said aprons.

The adjustment and the operation of the 90 parts will be readily understood from the above description and need no further description here. The handling of the vegetables, fruit or other articles by means of the yielding aprons prevents the possibility 95 of their being injured or crushed.

What I claim is:

1. A grading machine having a frame, a pair of aprons movably mounted on said frame, means for adjusting the aprons simultaneously to alter the angular relation 100 of their adjacent planes and means for driving the aprons.

2. A grading machine, comprising an inclined frame, coöperating aprons mounted in said inclined frame opposite to each other, rollers movably carrying the said aprons, adjustable frames for supporting the said rollers, means for simultaneously spacing the said frames with respect to each other at their upper and lower edges whereby they may be brought closer together at the bottom than at the top for accomplishing the grading operation, means for securing the upper edges of the aprons with respect to the upper ends of the supporting rolls thereof, whereby any tendency of the aprons to slip downwardly upon the rolls will be prevented, and means for directing 110 the assorted materials from the aprons into 115 different receptacles.

3. A grading machine comprising a frame, traveling aprons extending longitudinally of the frame, inclined rollers mounted in the upper and lower portions 125 of the said frame for moving and guiding the said aprons, frames loosely mounted in the machine and arranged to support the said rollers, bearings for the rollers mounted upon said frames, rods connected with 130

the said frames and extending to the side of the machine, sleeves for engaging the said screw rods, gearing for turning the said sleeves whereby the frames may be adjusted with respect to each other, and mechanism for rotating the rollers carrying the said aprons for accomplishing their operation...

4. A grading machine comprising a frame, inclined rollers journaled therein, aprons mounted on said rollers, a shaft for driving the rollers, gearing splined upon said shaft for permitting of the adjustment of the rollers, gears carried by the said rollers and meshing with the said splined gears, means for holding the gears with relation to each other, means for adjusting the rollers to varying relation of the aprons with respect to each other, and means for receiving materials placed between the aprons in separated and graded lots.

5. A grading machine comprising a frame, inclined rollers mounted therein, belts movably mounted upon said rollers, auxiliary belts carried by said rollers, means connecting the aprons with said auxiliary belts for preventing the aprons from work-

ing downwardly upon the inclined rollers, and means for driving the rollers for actuating the said aprons.

6. A grading machine comprising a frame, aprons movably mounted therein, frames carrying the said aprons and having a movable engagement with the main frame of the machine, shafting carrying said frames, sleeves having a screw threaded engagement with the said shafting, gears for operating said sleeves, sprocket gearing for connecting the gears at opposite ends of the machine, whereby when the frames are adjusted at one end of the machine the frames at the other end thereof will be adjusted to a similar degree, and means for driving the aprons for grading and delivering the vegetables, fruit or other articles in assorted lots.

In witness that I claim the foregoing I have hereunto subscribed my name this 23rd day of Oct., 1911.

GUSTAV THOMAS.
